UNITED STATES PATENT OFFICE

2,429,199

ADJUSTABLE HOSIERY FORM

Frank J. Bolek, Chicago, Ill.

Application September 5, 1946, Serial No. 694,980

4 Claims. (Cl. 223—75)

1

This invention relates to adjustable forms or frames for stretching and drying hosiery, and has particular reference to improvement of the type of device disclosed in U. S. Design Patent #128,-253, issued July 15, 1941, to John L. Devaney.

The primary object of the present invention is to provide simple and efficient means whereby the ankle portion of the form or frame may be readily adjusted to different ankle sizes.

The present invention also contemplates certain novel features and structural details which will become apparent from the following description when considered in connection with the accompanying drawing, in which:

Figure 1 is a side elevational view of an adjustable hosiery form constructed in accordance with the present invention.

Figure 2 is an edge elevational view thereof looking toward the right of Figure 1.

Figure 3 is an enlarged transverse horizontal section taken on line 3—3 of Figure 1.

Referring in detail to the drawing, the illustrated embodiment of the invention comprises a lower leg segment section 5 having an ankle portion 6 and a heel portion 7, and a U-shaped partial foot section 8.

The lower leg segment section 5 comprises spaced front and rear rods 9 and 10 which are joined at their upper ends to provide a transverse top member 11. The rods 9 and 10 terminate at their lower ends in forwardly directed or extended extensions 12 and 13, the rod 10 being formed to provide the heel portion 7.

The partial foot section comprises a toe member 14 consisting of a U-shaped piece of wire or rod having its ends fitted and secured in corresponding ends of tubular members 15 constituting the end portions of the partial foot section. The tubular members 15 slidably receive the extensions 12 and 13 whereby the partial foot section 8 may be adjusted to different foot length sizes.

A transverse brace 16 connects the rods 9 and 10 at the ankle portion 6, and this brace is adjustable as to length for adjusting the rods 9 and 10 to different ankle sizes. As is shown, the brace 16 comprises a rearwardly projecting stub 17 formed on or welded to the rod 9, a tubular member 18 having the stub 17 fitted and welded or otherwise secured in one end thereof, and an elongated rod 19 formed on or welded at one end to the rod 10 in line with and projecting toward the stub 17, the rod 19 being slidably and frictionally received in the tube 18. Sufficient frictional engagement is provided between the tube 55

2

18 and rod 19 to retain the brace in adjusted positions and maintain the ankle portion of the hose in proper stretched condition, while permitting forcible adjustment of the brace 16 as to length by manually moving the ankle portions of the rods 9 and 10 toward or from each other.

As generally shown in the above mentioned design patent, means is provided for adjusting the partial foot section 8 from a point adjacent the top of the form or frames. This means comprises an adjusting rod 20 extending to a point above the top transverse member 11 and formed at its upper end to provide a hook 21 by means of which the form or frame may be suspended from an elevated supporting rod or the like. The lower end portion 22 of the rod 20 is directed forwardly and downwardly and welded or otherwise attached as at 23 to the lower part of the toe member 14. The adjusting rod 20 is effectively guided by passing the same upwardly at one side of the brace 16 and at the opposite side of the transverse top member 11, as well as between the top member 11 and a laterally offset guiding cross piece 24 which connects the rods 9 and 10 25 a short distance below the transverse top member 11. The usual scale strip 25 is disposed longitudinally of and attached along one edge to the portion of the rod 20 directly below the hook 21 so that the graduations of this scale plate may 30 coact with either of the transverse members 11 or 24 to facilitate accurate adjustment of the partial foot section 8 through the medium of the rod 20. Obviously, in order to effect this adjustment from a point at or adjacent the top of the 35 form or frame, the rod 20 is simply moved upwardly or downwardly by using the hook 21 as a handle. It will thus be apparent that the adjustment of the partial foot section may be effected after initially placing the hose on the form or 40 frame for being stretched and dried. While the adjustable brace 16 primarily effects adjustment as to ankle size, it also provides for lesser adjustment affecting the calf and foot length sizes.

From the foregoing description, it is believed 45 that the construction, manner of use and advantages of the present invention will be readily understood and appreciated by those skilled in the art. Minor changes in details of construction and certain modifications may be made and 50 sorted to, such as fall within the scope of the invention as claimed.

What I claim is:

1. An adjustable hosiery form including a lower leg segment section having heel and ankle portions, and a U-shaped foot section, said lower

leg segment section comprising front and rear rods joined at the upper ends to provide a transverse top member, said rods terminating at their lower ends in forwardly directed and converging extensions, said foot section having rearwardly diverging tubular end portions slidably receiving said extensions whereby the foot section may be adjusted to different foot length sizes, and a transverse brace connecting the rods at the ankle portion and adjustable as to length for adjusting the rods to different ankle sizes.

2. The construction defined in claim 1, wherein said transverse brace comprises a tubular member attached at one end to one of said rods, and an elongated rod member attached at one end to the other of said rods and slidably frictionally telescoped into said tubular member, the frictional engagement between the rod member and the tubular member being sufficient to maintain adjustments of the transverse brace with the ankle portions of a hose in properly stretched condition upon the form.

3. The construction defined in claim 1, in combination with an adjusting rod for the foot section attached at one end to the toe portion of

the latter and extended upwardly between the front and rear rods to a point above the transverse top member, said adjusting rod passing to one side of the transverse brace and to the opposite side of the transverse top member, and a laterally offset cross member connecting the front and rear rods adjacent the transverse top member, said adjusting rod passing between said offset cross piece and said transverse top member.

4. The construction defined in claim 1, wherein said foot section comprises a U-shaped toe portion formed of wire, the end portions of the foot section comprising tubes having the ends of the toe portion fitted and secured in corresponding ends thereof.
